OTTO H. RODENBERG, OF CINCINNATI, OHIO

PILOT FOR FURNACES

Application filed July 15, 1929. Serial No. 378,820.

My invention relates to pilots for gas fired furnaces and oil burning furnaces, and particularly to gas pilots provided with an automatic control for governing the operation of the pilot.

In the art the use of pilots disclosing the general combination of elements involved in the particular type of pilot to which my invention relates has been quite extensively developed. The construction of such pilots is broadly as follows: There is an outer shell within which an expansion tube is mounted. The expansion tube is secured to the outer shell adjacent the end of the shell at a position in which a branch pipe extends at an angle to the tube and from the end of the branch pipe the gas flows in a stream to cause the ignition of the gas or oil in the main burners in the furnace. There are a series of small orifices in the tube in an exposed portion thereof adjacent the branch discharge pipe and a series of jets of gas burning from these orifices causes the tube to expand and, being fixed at one end, the tube expands through the outer end of the shell where it controls an electric switch which in turn governs a gas supply valve.

In pilots of the type described, if the branch pipe through which the pilot flame burns is at the end of the expansion tube there is some likelihood of the pilot flame becoming extinguished due to soot forming in the pipe, and there is thus considerable danger of explosion. It is the object of my invention therefore to so construct the branch discharge pipe that the danger of clogging up and thus causing the pilot flame to become extinguished will be minimized.

The above and other objects to which reference will be made in the ensuing disclosure I accomplish by that certain combination and arrangement of parts of which I have shown a preferred embodiment.

Referring to the drawings:—

Figure 1 is a plan view of the preferred type of pilot.

Figure 2 is a side elevation of the pilot.

Within the shell 1, having a cut-away portion 2 at the end thereof, which extends into the furnace, there is a tubular expansion pipe

3 secured to the shell as indicated at 4. The tube is thus fixed at its outer end. The inner end passes through the open end of the shell and has a slot 5 therein into which the gas to be supplied flows from an orifice 6 in the gas supply pipe 7. The tube has a piston 8 secured to its end which operates a switch 9 and thus, through an electric control valve (not shown), the flow of gas to the pilot is governed.

Extending at substantially a right angle from the end of the tube there is a branch pipe 10 through which gas may pass to the end 11 of the branch thus causing the pilot flame. In addition to the main branch pipe 10 there is a supplemental gas pipe 12 extending from a position in the gas expansion tube toward the inner of a row of expansion tube flame orifices 13 and joining the pipe 10 at 12a. The pipe 12 is provided with a slot 14 which extends from the end of the discharge opening 11 along the side of the pipe 12 until it bisects the tube 3 at 15 intermediate the row of expansion tube orifices 13.

The operation of the pilot is as follows: The shell extends horizontally into the furnace. From the orifices 13 a series of small jets of flame cause the expansion tube to heat up and expand causing the operation of the electric switch 9. Gas will flow out through the slot 14 as soon as there is enough to move than supply gas for the orifices 13 and the pilot flame issuing from the end 11 of the tube will always be ignited due to the continuous flame extending along the slot 14. The gas flowing from the slot 14 will always be ignited due to the opening 15 which will always be ignited by the flames issuing from the orifices 13. Should the pipe 10 become blocked up due to soot there will always be a free flow of gas through the supplemental pipe 12.

Thus I provide a pilot which minimizes the possibility of the pilot flame becoming extinguished, and while broadly the idea of the thermostatic control is old, it is my thought that I have added thereto a safety feature which will greatly promote the use of this type of pilot.

While I have only shown one specific ex-

ample of my invention, I include therein such changes in the positioning of the main and supplemental branch pipes as will occur to one skilled in the art and I consider such 5 mechanical modifications within the scope of my invention.

Having thus described my invention, what I claim as new and desire to secure by Letters Patent, is:—

10 1. A gas pilot comprising a shell having an expansion tube mounted within the shell and having an end of the tube fixed to a cut-away portion of the shell, said tube having a series of orifices extending along the tube in an exposed portion of the upper surface of the tube adjacent the end thereof, a branch pipe extending at an angle from the fixed 15 end of the tube, and a supplemental pipe extending across from the tube adjacent the orifices therein to said branch pipe.

15 2. A gas pilot comprising a shell having an expansion tube mounted within the shell and having an end of the tube fixed to a cut-away portion of the shell, said tube having a series of orifices extending along the tube in an exposed portion of the upper surface of the tube adjacent the end thereof, a branch pipe extending at an angle from the fixed 20 end of the tube, and a supplemental pipe extending across from the tube adjacent the orifices therein to said branch pipe, said tube having a slot extending through the side thereof.

25 3. A gas pilot comprising a shell having an expansion tube mounted within the shell and having an end of the tube fixed to a cut-away portion of the shell, said tube having a series of orifices extending along the tube in an exposed portion of the upper surface 30 of the tube adjacent the end thereof, a branch pipe extending at an angle from the fixed end of the tube, and a supplemental pipe extending across from the tube adjacent the orifices therein to said branch pipe, said tube 35 having a slot extending through the side thereof, and said slot bisecting the upper surface of the tube.

40 4. In a device of the character specified, a shell containing a thermostatic expansion tube through which gas flows to a pilot discharge, a branch pipe extending from a fixed 45 end of the tube at an angle to the tube, the end of said pipe comprising a discharge for the pilot flame, and an auxiliary pipe extending from the tube across to said branch pipe.

45 5. In a device of the character specified, a shell containing a thermostatic expansion tube through which gas flows to a pilot discharge, a branch pipe extending from a fixed 50 end of the tube at an angle to the tube, the end of said pipe comprising a discharge for the pilot flame, and an auxiliary pipe extending from the tube across to said branch 55 pipe, said auxiliary pipe having orifices ex-

tending through the side wall thereof, for the purposes described.

6. In combination in a gas pilot, a shell 70 having an expansion tube therein provided with a series of orifices extending along the tube adjacent the end thereof, a discharge port for the pilot flame, and a branch pipe leading from the tube intermediate the orifices to said discharge port.

7. In combination in a gas pilot, a shell 75 having an expansion tube therein provided with a series of orifices extending along the tube adjacent the end thereof, a discharge port for the pilot flame, and a branch pipe leading from the tube intermediate the orifices to said discharge port, said branch pipe 80 having discharging means extending from a side wall whereby a feeding flame from the orifices to the discharge port is provided.

8. In combination in a gas pilot, a shell 85 having an expansion tube therein provided with a series of orifices extending along the tube adjacent the end thereof, a discharge port for the pilot flame, and a branch pipe leading from the tube intermediate the orifices to said discharge port, said branch pipe 90 having discharging means extending from a side wall whereby a feeding flame from the orifices to the discharge port is provided, said discharging means arranged at such a 95 level in said pipe as to receive a supply of gas not consumed in said orifices.
